UNITED STATES PATENT OFFICE.

HUGH H. ROBERTSON, OF NEW YORK, N. Y., ASSIGNOR TO CONTINENTAL CAN COMPANY,
INCORPORATED, OF SYRACUSE, NEW YORK, A CORPORATION OF NEW YORK.

CAP FOR BOTTLES OR JARS.

1,132,975.

Specification of Letters Patent. Patented Mar. 23, 1915.

Application filed July 3, 1913. Serial No. 777,283.

To all whom it may concern:

Be it known that I, HUGH H. ROBERTSON, a citizen of the United States, residing at New York, in the county of New York, 5 State of New York, have invented certain new and useful Improvements in Caps for Bottles or Jars, of which the following is a description, reference being had to the accompanying drawing and to the figures of 10 reference marked thereon.

The invention relates to new and useful improvements in caps for bottles or jars and more particularly to caps made from sheet metal by cutting and bending in contradistinction to being drawn.

The purpose of the invention is to provide a metal cap which may be made from sheet metal which has been lacquered prior to the forming of the cap and to produce a cap 20 wherein the exposed surfaces in the finished cap are entirely covered by the lacquer.

In the drawings, which show by way of illustration one embodiment of the invention, Figure 1 shows a sheet metal blank 25 bent to form the cylindrical body portion of the cap; Fig. 2 is a top plan view of the same; Fig. 3 is a longitudinal sectional view, showing the top inserted in the cylindrical body portion and prior to the bending 30 of the body portion and top to join the same; Fig. 4 is a longitudinal sectional view through the finished cap; Fig. 5 is a side view of the same; and Fig. 6 is a top plan view. Fig. 7 is a detail in section 35 showing a modified form of cap.

The invention consists generally in a sheet metal cap which is made from sheet metal having its surfaces coated with lacquer prior to the formation of the cap and 40 wherein the cap is formed by cutting and bending the metal in contradistinction to drawing the metal. The body portion of the cap is cut from the sheet metal and formed into a cylinder and its edges are united in 45 such a manner as to conceal and cover the raw edges of the metal formed in the cutting of the blank. The top of the cap is also cut from the lacquered sheet and is attached to the cylindrical body portion in

such a manner that the raw edges of the 50 metal formed in the cutting of the top and the raw edges of the material at the upper edge of the cylindrical body portion are both concealed or covered. The lower edge of the cylindrical body portion may also 55 be formed so as to cover the raw edges of the material so that in the finished cap all the exposed surfaces of the cap will be lacquered.

Referring more in detail to the drawing, 60 my improved cap consists of a body portion 1 and a top 2. This body portion 1 is formed by cutting a blank from a sheet of metal after the same is coated with lacquer as above noted. The blank is then rolled 65 into cylindrical form and the meeting edges joined by interlocking the edges, as clearly shown in Fig. 2, so that the edge 3 entirely covers and conceals the raw edge 4, while the folded edge 5 entirely covers and 70 conceals the raw edge 6. It will be understood that by the raw edge of the metal, I have reference to the exposed steel formed in the cutting of the coated sheet of steel. These raw edges if exposed will rust and corrode, 75 but by the above construction of seam, I am able to entirely cover and conceal these raw edges of the metal.

The side seam 7 of the cylindrical body portion 1 terminates short of the top, as 80 clearly shown in Fig. 1. The top for the body portion is also cut from a sheet of metal coated with lacquer, and said sheet may also be ornamented in any desired way, as illustrated for example in Fig. 6. It will be understood that the sheet after being coated is 85 ornamented, and then the disks to form the tops are cut, so that the ornamentation is properly centered in each disk. The disk forming the top 2 is bent so that the edges 90 are turned upwardly as at 8, (see Fig. 3). This top is then inserted in the cylindrical body portion 1 of the cap, and is crowded into the same a sufficient distance so the edge 9 of the body portion extends above 95 the extreme upper edge 10 of the top 2. The upper edge of the body portion 9 is then bent by means of a die or otherwise, about

the edge 8 of the top. At the same time that this die is operating to fold or bend the upper edge of the body portion over the upwardly extending edge of the top, the 5 center part of the top is crowned upwardly, as at 11, so as to bring the upper outer face of the top substantially into the plane of the extreme upper edges of the seam joining the top to the body of the cap. This crowning 10 of the top brings the ornamented surface thereof flush with the top of the cap, and it also bends the metal so as to further conceal and cover the raw edge of the metal 15 at the upper edge of the body of the cap.

15 Referring to Fig. 4, it will be noted that the edge 8 is folded within the bent over part of the upper edge of the body of the cap, while the edge 9 of the body of the cap is folded in between the edge 8 and the upwardly crowned part of the top, so that both 20 of these raw edges, as above noted, are entirely covered and concealed. The cap may be then formed with a screw thread 12, by which it is attached to a suitable screw 25 thread at the mouth of the bottle or jar in the usual manner. It may also be formed with vertical ribs, as at 13, which assist in turning the cap to screw the same on or off from the bottle or jar. These vertical ribs 30 and the screw threads of the cap, are of the usual construction, and have no part in my present invention.

From the above construction, it will be apparent that I have provided a metal cap 35 wherein the entire cap is made by cutting and bending the metal and the top is joined firmly to the body portion of the cap by a seam wherein the raw edges of the material are entirely concealed and covered.

40 In Fig. 7 of the drawings I have shown a slightly modified form of the invention, as the cap, as shown in this figure, has the lower edge thereof rolled or folded, as at 45 14, so as to prevent forming a sharp edge of metal at the lower edge of the cap, and, furthermore, to substantially conceal and cover the exposed or raw edge of metal formed in the cutting of the blank for the body portion of the cap.

50 From the above construction it will be apparent that in Fig. 7 I have shown a construction of cap wherein all the raw edges of metal formed in cutting the metal from the sheet are substantially covered and concealed.

55 While I have described my invention as particularly adapted for forming a bottle cap from lacquered sheet metal, it is to be understood that the metal may be coated 60 with other substances than lacquer and if metal is used it must be of a character to provide a non-corroding surface.

It is obvious that minor changes in the details of construction may be made with-

out departing from the spirit of the invention as set forth in the appended claims.

Having thus described my invention, what I claim as new and desire to secure by Letters Patent, is:

1. A lacquered sheet metal cap for bottles 70 or jars comprising a body portion cut from sheet metal lacquered on both surfaces thereof throughout, said body portion being bent into cylindrical form and having the meeting edges thereof joined by an interfolded seam which conceals and covers the exposed raw edges of the metal formed in cutting the body portion, and a top for closing the end of said body portion, said top being cut from a sheet of metal lacquered 80 on both sides thereof throughout, said top being joined to the body portion by an interfolded seam which conceals and covers the exposed raw upper edge of the metal of the body portion and the exposed raw 85 edge of the metal of the top formed in cutting the top.

2. A lacquered sheet metal cap for bottles or jars comprising a body portion cut from sheet metal lacquered on both surfaces thereof throughout, said body portion being bent into cylindrical form and having the meeting edges thereof joined by an interfolded seam which conceals and covers the exposed raw edges of the metal formed in cutting 95 the body portion, and a top for closing the end of said body portion, said top being cut from a sheet of metal lacquered on both sides thereof throughout, said top being joined to the body portion by an interfolded 100 seam which conceals and covers the exposed raw upper edge of the metal of the body portion and the exposed raw edge of the metal of the top formed in cutting the top, said top being bent so as to be substantially flush with the extreme upper part of the seam joining the top to the body portion, the lower edge of said body portion being bent upwardly to conceal the raw edge 105 of the metal at the bottom of the body portion and to stiffen the body of the cap, said body portion having a screw-thread formed 110 therein.

3. A sheet metal cap for bottles comprising a body portion cut from sheet metal 115 coated on both surfaces thereof throughout, said body portion being bent into cylindrical form and having the meeting edges thereof joined by an interfolded seam which conceals and covers the exposed raw edges 120 of the metal formed in cutting the body portion, and a top for closing the end of said body portion, said top being cut from a sheet of metal coated on both sides thereof throughout, said top being joined to the body portion by an interfolded seam which conceals and covers the exposed raw upper 125 edge of the metal of the body portion and

the exposed raw edge of the metal of the top formed in cutting the top, the lower edge of said body portion being bent upwardly to conceal the raw edge of the metal
5 at the bottom of the body portion and to stiffen the body of the cap, said body portion having a screw-thread formed therein.

In testimony whereof, I affix my signature, in the presence of two witnesses.

HUGH H. ROBERTSON.
